T '19.5.

FIG. 1 is a perspective view of a bottle carton showing my new design;

FIG. 2 is an enlarged section taken along 2—2 of FIG. 1;

FIG. 3 is a fragmentary end elevation taken along line 3—3 of FIG. 1;

FIG. 4 is a fragmentary perspective view of a modified form of the design of FIG. 1;

FIG. 5 is a fragmentary end elevation of the tab portion of FIG. 4;

FIG. 6 is a fragmentary perspective view of a second modified form of the design of FIG. 1;

FIG. 7 is a fragmentary end elevation of the tab portion of FIG. 6;

FIG. 8 is a fragmentary perspective view of a third modified form of the design of FIG. 1;

FIG. 9 is a fragmentary end elevation of the tab portion of FIG. 8;

FIG. 10 is a fragmentary perspective view of a fourth modified form of the design of FIG. 1; and

FIG. 11 is a fragmentary end elevation of the tab portion of FIG. 10.

The side opposite that shown in FIG. 1 is substantially similar to that shown; the end opposite that shown is substantially similar except the tabs are omitted therefrom; and the bottom is substantially plain and unornamented.

The drawings are lined for the color red, but this is not critical to the present invention and any color may appear on the tabs.

The characteristic features of my new design for a bottle carton reside in the ornamental tab which is fashioned in the shape of a drinking vessel at the end of such a carton.

This is a continuation-in-part of design application Ser. No. 20,471, filed Dec. 3, 1969, and now abandoned.

I claim:

The ornamental design for a bottle carton, substantially as shown and described.
